UNITED STATES PATENT OFFICE.

JOHN H. STOKESBARY, OF HIGHLANDS, COLORADO, ASSIGNOR OF THREE-FOURTHS TO ROBERT H. PORTER AND FRANK P. ARBUCKLE, OF SAME PLACE.

EARTH-BORING APPARATUS.

SPECIFICATION forming part of Letters Patent No. 469,219, dated February 16, 1892.

Application filed April 7, 1891. Serial No. 387,917. (No model.)

To all whom it may concern:

Be it known that I, JOHN H. STOKESBARY, a citizen of the United States, residing at Highlands, in the county of Arapahoe and State of Colorado, have invented certain new and useful Improvements in Earth-Boring Apparatus; and I do hereby declare the following to be a full, clear, and exact description of the invention, such as will enable others skilled in the art to which it appertains to make and use the same.

This invention relates to earth-boring machines, and particularly to such as are used for horizontal boring or tunneling, for laying pipes understreet-pavements, lawns, &c.; and it consists in certain improvements therein, as will be hereinafter fully set forth, and pointed out in the claims.

The invention is illustrated in the accompanying drawings, as follows:

Figure 1 is a perspective and transverse sectional view of a city street showing my device in operation therein. Fig. 2 is a side elevation of the auger, stem, stock-feeding lever, &c., shown in Fig. 1, considerably enlarged. Fig. 3 shows the swivel C and C' in vertical longitudinal section and the valve E in elevation on a larger scale than that shown in Fig. 7. Fig. 4 is a longitudinal section of the bit or auger. Fig. 5 shows the same parts seen in Fig. 2, with an alternative form of operating mechanism, said parts being in side elevation. Fig. 6 is a vertical transverse section on the line y y in Fig. 5, looking in the direction of the arrow. Fig. 7 is a similar view taken on the line x x in the said Fig. 5.

In operating my device a hose B connects a water-pipe A or hydrant with the device back of a regulating-valve E, and water is supplied through the hollow stem, sections G, and auger-bit H to the cutting-point, and the earth is thereby softened and the cuttings or débris are washed back through the bore to the starting-point or pit in which the machine is being operated.

The construction and operation of my device is as follows:

H is the bit or auger, which has cutting-blades H' and an opening H² through its body

from the shank to a point between the two blades. The auger stems or rods G are made of ordinary iron tubing in sections of convenient length. The bit H is connected with one of the sections G by a screw or other ordinary or convenient coupler, and the other sections are added as the work of boring progresses.

In the construction shown in Figs. 1 and 2 there is a loop F of tubing formed in convenient form to act like a common bit-stock, and the auger-rods G are coupled with one end of this loop, and the loop is connected at the other end with a swivel-stem C', which fits in a swivel-barrel C, and has a gudgeon-bearing C² in a block c³ within the barrel C. A stuffing-box C⁷ at the end of the barrel C forms a close joint around the swivel-stem C', so no water will escape at the point. The swivel-stem C' is hollow and has an opening or slot C⁸ in the side, so that water entering the barrel C can flow through the stem C'.

Connected with the barrel C is a common valve E, of any desired construction, and to its shank b is connected a hose B, which may be connected with any source of water-supply, such as a hydrant or the main A.

In practice the swivel-stem C', when the pipe or section G to which it is secured is turned, rotates in but imparts no rotative movement to the swivel-barrel C. This barrel, however, imparts the forward movement to the section G when pressed forward by the lever D. In such a movement the block c⁶ presses against the conical end of the swivel-stem, and at the same time forms a bearing 85 for the stem to revolve in, so that said stem will move forward with the swivel-barrel. When the valve E is opened, water will flow through the swivel C C', thence through the crank-loop F, and thence through the auger-stem sections G, and be discharged through the orifice H², between the cutting-blades H', whence it will impinge upon the earth and aid the action of the cutting-blades H'. The water thus discharged will find its way back 95 through the boring and carry with it the débris.

The auger is fed to its work by a lever D,

which is pivoted to the swivel at d' , and to a foot-piece D' , which is sustained at d against the wall of the working pit.

In the construction shown in Figs. 5, 6, and 5 7 the auger-stems are operated by a power device in place of by the crank-loop F ; otherwise there is no difference in construction.

J represents a frame-work secured by its rear end to the stuffing-box c of the swivel-barrel C , and having bearings for the swivel-stem C' , provided with the bevel ratchet-gears $L L'$, which mesh with the cogs k on a driving-gear K , having the operating-lever K' and journaled to frame J at j . The ratchets b are 10 preferably formed integral with the bevel-gears. The teeth on each ratchet are turned in opposite directions and the movement in one direction is controlled by a pawl l , pivoted on the swivel-stem, one for each ratchet. (Shown 15 in Fig. 6.) The bevel ratchet-gears $L L'$ are loose upon the shaft and are only held against rotation on the swivel-stem by its pawl, when the gear k , meshing with it, is moved down, the effect being to rotate the swivel-stem. At 20 the same time the other gear ratchet-wheel is rolling upon its gear k and upon the swivel-stem and continues to do so till the driving-gear K , rocked in the opposite direction from that in which it has been moving, when it rotates the second gear ratchet-wheel and the 25 swivel-stem, while the first gear ratchet-wheel rolls upon its gear K and the swivel-stem, thereby giving to the swivel-stem a rotative movement in one direction continuously.

30 35 What I claim as new is—

1. In an earth-boring machine, the combination of a water-conveying auger-stem and auger and a water-conveying swivel connecting said auger-stem with a source of water-supply, means for rotating said auger, and a

lever D , pivoted on said swivel and having a foot-piece, for the purpose set forth.

2. In an earth-boring machine, the combination of a hollow auger H , a hollow auger-stem G , connected with said auger, a hollow 45 swivel-stem C' , connected with the auger-stem, a barrel C , in which stem C' is swiveled, a water-supply pipe connected with said barrel C , means for rotating said auger, and a lever D , fulcrumed upon said barrel or other 50 part and having the foot D' , for the purpose set forth.

3. In an earth-boring machine, the combination of a water-conveying auger-stem and auger and a water-conveying swivel connecting said auger-stem with a source of water-supply, ratchet-pinions on said swivel, an operating gear-wheel acting upon said pinions and having lever K' , and a lever D , pivoted on said swivel and having a foot-piece D' , 55 for the purpose set forth.

4. In an earth-boring machine, the combination of the auger-stem, the swivel-stem having the opening c^3 in its periphery and the conical point c^2 , the swivel-barrel C' , having 65 concaved block c^6 and a water-supply, means for rotating the swivel and auger stems, and means for advancing said stems and barrel, for the purpose set forth.

5. The combination of an auger, means for 70 rotating the auger, and a lever D , fulcrumed on the auger and having a foot-piece, for the purpose set forth.

In testimony whereof I affix my signature in presence of two witnesses.

JOHN H. STOKESBARY.
